UNITED STATES PATENT OFFICE.

JOHN T. AUSTIN, OF HARTFORD, CONNECTICUT, ASSIGNOR TO AUSTIN ORGAN COMPANY, OF HARTFORD, CONNECTICUT, A CORPORATION OF MAINE.

DESIGN FOR AN ORGAN-STOP KEY.

45,320.

Specification for Design.

Patented Mar. 3, 1914.

Application filed August 22, 1913. Serial No. 786,168. Term of patent 14 years.

To all whom it may concern:

Be it known that I, JOHN T. AUSTIN, a citizen of the United States, residing at Hartford, county of Hartford, State of Connecticut, have invented a new, original, and ornamental Design for an Organ-Stop Key, of which the following is a specification, reference being had to the accompanying drawing, forming a part thereof, and in which—

Figure 1 is a plan view of an organ stop key showing my new design, and Fig. 2 is an edge view of said organ stop key illustrating my said new design.

2 denotes the shank of the key and 3 denotes the finger portion which is located at the front of the key. The sides of the finger or tip portion are along symmetrical forwardly converging angles.

I claim:

The ornamental design for an organ stop key substantially as shown.

JOHN T. AUSTIN.
